US00D583791S

(12) **United States Design Patent**
Minamide et al.

(10) **Patent No.:** US D583,791 S
(45) **Date of Patent:** ** Dec. 30, 2008

(54) **MOBILE PHONE**

(75) Inventors: **Keiichi Minamide**, Tokyo (JP);
Jong-Seong Lee, Seoul (KR); **Yusuru
Masuda**, Tokyo (JP)

(73) Assignee: **Samsung Electronics Co., Ltd.**,
Suwon-Si (KR)

(**) Term: **14 Years**

(21) Appl. No.: **29/300,710**

(22) Filed: **Apr. 29, 2008**

(30) **Foreign Application Priority Data**

Dec. 28, 2007 (KR) 30-2007-0054145

(51) **LOC (8) Cl.** 14-03

(52) **U.S. Cl.** ..... D14/138 AB

(58) **Field of Classification Search** D14/138,
D14/496, 341-347; 455/575.3, 575.1

See application file for complete search history.
